UNITED STATES PATENT OFFICE.

EDWARD BAGLEY, OF VANCOUVER, BRITISH COLUMBIA, CANADA.

FINE-GOLD-SAVING MACHINE.

1,256,764.

Specification of Letters Patent. Patented Feb. 19, 1918.

Application filed May 24, 1917. Serial No. 170,757.

To all whom it may concern:

Be it known that I, EDWARD BAGLEY, a subject of the King of Great Britain, residing at Vancouver, in the Province of British Columbia, Canada, have invented certain new and useful Improvements in Fine-Gold-Saving Machines, of which the following is a specification.

This invention relates to a machine for the recovery of fine gold from the gold bearing sand or gravel of river benches, river beds or of beaches, and is designed to supplement the customary ground sluicing methods, by recovering the fine gold from the dirt in a simple and effective manner before delivery of the same to the sluice boxes or other gold recovery means.

While the machines in common use will recover ordinary fine gold considerable loss 20 is unavoidably sustained of the fine gold carried in suspension by the water washing the gravel.

In the machine, which is the subject of this application, this loss is overcome by continuously delivering the wash dirt through a revolving cylindrical screen of wire mesh set at a slight incline within a tank of water which is quiescent to the extent that there is no sensible flow through it. The gravel 30 as washed is delivered to the sluice boxes for recovery of any coarse gold, and the fine sand, washed through the mesh of the screen, settles in the corrugated bottom of the tank in which the screen rotates and is loosened and continuously worked toward the lower end by angled blades secured to and projecting radially from the framework of the cylindrical screen.

Free quicksilver is placed in parallel 40 riffles or corrugations of the tank and amalgamated plates are distributed at intervals apart therein, so that any fine or float gold settling with the sand is recovered during progression of this sand to the lower end of the tank and the sand is delivered therefrom through a distributer over amalgamated plates and finally over concentrating tables for the recovery of any black sand or other value carrying metals.

The important features of the invention are the primary washing of the "dirt" in substantially quiescent water, and the separation of the fine sand from the gravel before delivery of the latter to the sluices; the 50 provision of amalgamating means within the tank and the loosening of the sand by

the blades and its slow progression over the amalgamating means to the delivery end of the tank.

The machine is fully described in the following specification, reference being made to the drawings by which it is accompanied, in which:

Figure 1 is a vertical longitudinal section through the machine.

Fig. 2 is a cross section on the line 2—2 in Fig. 1, looking in the direction of the arrow.

Fig. 3 is a cross section on the line 3—3 in Fig. 1 looking in the direction of the arrow 3, and

Fig. 4 is a plan of the distributer.

In these drawings 9 represents a semi-cylindrical tank of corrugated metal, which is suitably supported at a slight incline 75 within the frame 10 to which the several parts of the machine are attached or connected. Rotatably mounted concentric with this tank 9 and at a corresponding incline is a cylindrical wire mesh screen 2 which is 80 secured in sections on an angle iron frame extending between the ends 3 and 4 by which it is supported. One end 3 of this screen is centrally apertured at 5 to receive a chute 6 through which the washed dirt is delivered 85 to within the screen and this end 3 is supported on rollers 23 to rotate on the axis of the screen under the action of a worm 17 engaging the teeth of a worm wheel secured to or integral with the upper end 3.

The lower end 4 of the screen is supported on the outwardly projecting end of a shaft 7 which passes through its center and is carried in a bearing 8 on the frame 10. From the lower end of the tank 9 a pipe 11 controlled by a stop-cock delivers into the central basin 12 of a distributer 13, and into the upper end is inserted a water service pipe 14 to replace the water withdrawn with the sand through the pipe 11.

Secured to the ends 3 and 4 of the screen where they project beyond the circumference thereof, and to an intermediate support, if necessary, are bars 15 parallel to the axis of rotation of the screen and on these 105 bars blades 16 are secured at intervals apart to project radially to just clear the inside of the tank 9. These blades are angled slightly to progress the sand gradually over the corrugations of the tank toward the lower end.

In the lower end 4 of the screen are diametrically opposed circumferentially elong-

gated apertures 18, the following sides of which in the direction of rotation have scoops 19 projecting into the interior of the screen, which divert the washed gravel from the screen into passages 20 in the end 4, which passages being separated from one another elevate the gravel above the level of the tank as the screen rotates and deliver it through openings 21 onto a chute 22 for delivery into sluice boxes for the recovery of coarser gold.

It must be distinctly understood, that, as stated in the preamble to this specification, the machine is specifically designed for washing the finer sand and its contained values from the coarser gravel, and for the recovery of any fine gold from the sand so washed.

In use, the washed dirt is delivered through the chute 6 to within the cylindrical screen 2 which operates within the tank 9 and this tank is maintained full of water to the level of its lower upper edge. The rotation of this screen at an incline carries the material to the lower end during which movement in water the fine sand with which the gravel is associated is washed from it and passes through the interstices of the screen into the tank 9, while the washed gravel is withdrawn from the lower end of the screen through the scoop outlets 18 and passages 20, 21 and is delivered over the chute 22 to the sluice boxes.

As the water in the tank 9 is practically quiescent so far as current or flow is concerned, the sand, which passes through the screen and any fine gold or black sand associated with it, will settle in the bottom of the tank and is continuously loosened by the blades 16 that the heavier metal may pass through it to come in contact and be amalgamated with the free quicksilver in the riffles of the bottom of the tank, or to adhere to any of the amalgamated plates 25 disposed therearound. The sand is simultaneously progressed slowly by the angle of these blades toward the lower end of the tank where it may be drawn off continuously or at intervals as desired, through the pipe 11 to be distributed over the surface of the amalgamating plates 23 of the concentrating tables 24 to recover any escaping particles of gold amalgam and the black sand or the like.

An important feature of the invention lies in the fact that the fine sand which may carry gold and other values is washed from the gravel, to be separately treated, and therefore the gold saving means suited to the recovery of fine gold, is not subjected to the scour and wear of the heavier gravel; Further, that fine gold is amalgamated in the tank either with free quicksilver or by means of amalgamated plates before the sand is delivered to the concentrating tables, whereby

the concentration is rendered more easy of accomplishment, as the particles of amalgam are necessarily heavier and collect more readily than flour gold.

Having now particularly described my invention, I hereby declare that what I claim as new and desire to be protected in by Letters Patent, is:

1. A gold washing machine, comprising in combination, an elongated tank having a reduced area adjacent the bottom and riffles across that reduced area, said tank being provided with a delivery aperture from the bottom of one end and a water delivery adjacent the other end, a cylindrical screen rotatable within the length of the tank on an axis of rotation substantially parallel to the bottom of the tank, said screen having angled blades projecting outwardly from it, a chute delivering the gravel to be washed within the screen, means for delivering the washed gravel from the opposite end of the screen, and means within the tank for amalgamating with quicksilver any fine gold that may pass through the screen, the said delivery aperture being restricted and adapted to maintain a body of pulp in the tank in contact with the screen and the blades thereon substantially as shown and described. 95

2. A gold washing machine, comprising in combination, a semi-cylindrical tank having circumferential corrugations, said tank having a discharge aperture at the bottom of one end and a water delivery adjacent the other end, a cylindrical mesh screen rotatably supported within the tank to be concentric with the bottom of it, said screen having angled blades projecting from its outer side to sweep the interior of the tank and progress the contents toward the discharge aperture, means for delivering gravel to be washed to within the rotatable screen, and means for delivering the washed gravel from the opposite end of the same, said discharge aperture being restricted and adapted to maintain a body of pulp in the tank in contact with the screen and the blades thereon. 105

3. A gold-washing machine, comprising in combination, a semi-cylindrical tank having circumferential corrugations, said tank being supported at a slight incline from the horizontal and provided with a discharge aperture at the bottom of the lower end and a water delivery adjacent the upper end, a cylindrical mesh screen rotatably supported with the tank to be substantially concentric with the bottom of it, said screen having angled blades projecting from it outside the screen to sweep the interior of the tank and progress the contents toward the lower end, means for delivering gravel to be washed to within the rotatable screen, means for delivering the washed gravel from the opposite end of the same, and means for 110

amalgamating with quicksilver any fine gold that may be in the tank, said discharge aperture being restricted and adapted to maintain a body of pulp in the tank in contact with the screen and the blades thereon.

4. A gold washing machine, comprising in combination, a semi-cylindrical tank having circumferential corrugations, said tank being supported at a slight incline from the horizontal and provided with a controlled discharge aperture at the bottom of the lower end and a water delivery adjacent the upper end, a cylindrical mesh screen rotatably supported within the tank to be substantially concentric with it, said screen having angled blades projecting from its outer side to sweep the interior of the tank, means for delivering gravel to be washed to within the rotatable screen, means for delivering the washed gravel from the opposite end of the tank, and means within the tank for amalgamating any fine gold with quicksilver, said discharge aperture being restricted and adapted to maintain a body of pulp in the tank in contact with the screen and the blades thereon.

In testimony whereof I affix my signature.
EDWARD BAGLEY.
